EXTENSION TABLE

Charles F. Vance, Winston-Salem, N. C.

Original application April 20, 1936, Serial No. 75,435. Divided and this application February 18, 1938, Serial No. 191,347.

1 Claim. (Cl. 311—74)

This invention relates to an improvement in extension tables, and this application is a division of application Serial No. 75,435, filed by me in the United States Patent Office April 20, 1936.

5 One object is to provide an assembly which includes equalizers along with the remaining co-operating mechanism for preventing binding of the parts in opening and closing the table.

In order to accomplish this purpose, suitable 10 equalizing means are provided and these are disposed between the table ends, so that when one of the leaves is moved, the other leaf will be simultaneously moved a corresponding amount in the opposite direction.

15 In the accompanying drawings:

Fig. 1 is a top plan view with the end leaves shown in dotted lines;

Fig. 2 is an isometric view of one side of the structure shown in Fig. 1;

20 Fig. 3 is a cross-sectional view taken along the line 3—3 of Fig. 1; and

Fig. 4 is a cross-sectional view taken along the line 4—4 of Fig. 1.

25 Trackways 21 and 21' have mounted therein suitable movable U-shaped members 115, 116, 117 and 118, and balls 31 are provided to facilitate the easy movement between the members 21 and 21' and the members 115 to 118 inclusive. The members 115 to 118 inclusive have mounted 30 thereon suitable angle members 119, 120, 121 and 122 to which the table top leaves 123 and 124 are secured. The vertical web of U-shaped members 117 and 118 have strap members 125 and 126, respectively, secured thereto, which strap members project inwardly toward the center of the 35 table and have pivotally secured to the ends thereof as at 127 and 128, suitable links 129 and 130. These links are also pivotally connected as at 131 and 132 to crossed levers 133 and 134, said levers being pivotally secured at a common point 40 135 which is equidistant from the Z-shaped members 22 and 22' and they are pivotally supported on an arm 137 projecting from one of the struts 42 of the inner frame of the mechanism, 45 to a strut 136, which latter is secured at its ends to the Z-shaped members 22 and 22'.

Levers 133 and 134 have suitable slots 140 and 141 in their other ends which are adapted to cooperate with slots 142 and 143 in the outstand-

ing leg of angle straps 144 and 145, said straps being secured to angle members 120 and 119, respectively, to loosely and movably receive the bolts 146 and 147. It is evident that in providing an arrangement of this type when the table top 123 for instance, is moved to the left in Figure 1, the table top 124 will be caused to move to the right since the lever and link arrangement comprising members 129, 130, 133 and 134 with their associated parts will produce an equalizing effect. 10

The trackways 21 and 21' have suitable stops 149 disposed midway therein for limiting the inward movement of the movable members 115 to 118 inclusive should the table tops 123 and 124 not be connected thereto. This is especially important during the shipment of the unit assembly which is usually done before the table tops and the supports are connected. 15

It is evident that reasonably satisfactory results could be obtained by employing only one 20 of the levers 133 or 134 and their associated parts. For example, lever 133, link 129 and the lug angles 125 and 144 could be used which would provide a connection between the movable members 116 and 117. With only these two members connected, 25 if the table tops 123 and 124 were properly secured to the members 119 to 121 inclusive, the movement of one table top or leaf would produce an opposite movement in the other. However, in order to absolutely insure against binding, it has 30 been found preferable to use a pair of levers.

I claim:

In an extension table, the combination of rail members in spaced parallel relationship, extension leaves supported by and slidably connected therewith, an inner frame comprising slides and ends, the latter secured between and to the centers of the rail members, a strut outside of the frame and parallel to the sides thereof, a brace extending from the center of the strut to one side of the frame, a lever pivoted at its center to the center of the strut, a link pivotally connected with one end of the lever and extending directly across the inner frame, and having its other end pivotally connected with one of the extension leaves, and the other end of the lever having a sliding pivotal connection with the other extension leaf. 40 45

CHARLES F. VANCE.
